UNITED STATES PATENT OFFICE.

PRIMUS OTTO DORER, OF LONDON, ENGLAND, ASSIGNOR TO S. SMITH & SONS (MOTOR ACCESSORIES) LIMITED, OF LONDON, ENGLAND.

BEZEL-WOUND TIMEPIECE.

1,301,919.

Specification of Letters Patent. Patented Apr. 29, 1919.

Application filed November 23, 1917. Serial No. 203,613.

To all whom it may concern:

Be it known that I, PRIMUS OTTO DORER, British subject, residing at London, England, have invented certain new and useful 5 Improvements in Bezel-Wound Timepieces, of which the following is a specification.

This invention is for improvements in or relating to bezel-wound time-pieces of the type wherein the winding-mechanism connecting the bezel to the spring is situated at the front of the movement.

It has been previously proposed to provide time-pieces with the ordinary rocking-lever winding-mechanism, such as is employed in a watch for winding and setting the hands, situated behind the dial at the front of the movement and geared to the bezel by means of an internally toothed ring carried on the bezel. This mechanism involves a considerable number of parts and the object of the present invention is to provide a more simple arrangement although still having the mechanism situated between the dial and the movement.

According to this invention, the movement carries a central hollow and forwardly-projecting stationary pillar. The main spring surrounds this in front of the movement and has its inner end attached to a driving wheel 30 mounted on the pillar and its outer end to a part, for example a barrel, movable with the bezel and controlled by a one-way clutch.

The invention comprises also certain subordinate features which will be referred to 35 in the course of the description of the accompanying drawings, wherein—

Figure 1 is a vertical central section of one construction of bezel-wound clock according to the present invention, and

40 Fig. 2 is a similar view of an alternative construction thereof.

Dealing first with the construction illustrated in Fig. 1, the movement frame, which comprises the front plate M^1 , the back plate M^2 and the pillars Q , carries the movement between the two plates M^1 and M^2 . The front plate M^1 supports a central hollow and forwardly projecting stationary pillar P se-

cured to it by a nut N . The main-spring MS surrounds this pillar in front of the 50 movement, and the inner end i of the main-spring is attached to a driving-wheel W mounted on the pillar, and its outer end to a barrel B , movable with the bezel Z . The rotation of this bezel is controlled by a one-way clutch which may be of any usual or well-known type. In the construction illustrated, this clutch comprises a pawl A , which is mounted on the plate M' and engages with ratchet teeth B' , formed on the barrel B . 55 The inclosing member for the spring, that is to say the barrel B , is mounted to rotate freely around the central pillar P between the front plate M^1 of the movement and the stationary dial D , and in the drawing the 60 bezel is shown as connected direct to the barrel. The lower edge of the barrel bears upon a flange F on the front plate M^1 . There is a cover-plate CP at the front or top end of the barrel B over the spring. 65 The central portion of this cover-plate is flanged at CP^1 and encircles the upper end of the pillar P , so that the cover-plate thus constitutes both a cover for the barrel B and a support for the forward end of it. 70 The movement, of which the plates M^1 and M^2 are the front and back plates respectively, can be secured in any convenient manner to the bottom of an outer casing C through the face of which the upper end 75 of the barrel B extends to meet the bezel Z . The casing is closed in at the front by the bezel containing the usual front glass FG .

The bezel Z forms a shoulder which bears upon the exterior of the casing C and serves 85 to steady the whole construction. The attachment of the bezel to the barrel may be effected in any convenient manner.

The spring does not fill the whole depth of the barrel, but a false bottom FB is provided as a shield for preventing the main spring fouling the gear wheel W and the pinion S meshing therewith. This false bottom has the form of a plate supported at the center by a flange W^1 on the driving 90 wheel W . The said plate is further sup-

ported by feet such as FB¹ extended downward from it to bear on the front plate of the movement. The driving wheel W is geared in any usual or convenient manner 5 to the train in the movement by a pinion S contained in the space below the false bottom or shield FB, that is to say between the false bottom FB and the front plate M¹ of the movement.

10 The winding of the spring is effected by turning the bezel Z and thus the exterior wall of the spring-barrel B, and to prevent return movement of the barrel, any convenient one-way clutch mechanism may be 15 used; for example teeth might be formed on the exterior of the barrel or on a part secured thereto, and a pawl could be mounted on the front plate of the movement to co-operate therewith. Or, alternatively, the 20 exterior of the barrel could be surrounded by a spiral of wire having one end fixed relatively to the movement and the other end free, so that the barrel can be turned freely in one direction to loosen the spiral, but 25 cannot be turned in the reverse direction. Such one-way clutches are in themselves well-known and do not *per se* constitute any part of the present invention.

The winding parts are all kept in place 30 by the flange P¹ on the forward end of the central pillar P, which flange serves to receive the dial D already mentioned as secured to it.

The motion-work for the hands may be 35 mounted between the plates M¹ M², and a set-hand spindle SH can extend, as shown, from the front of the outer casing C to a point near one of the wheels of the motion-work. This spindle extends out from the 40 casing to a point beyond the bezel and does not interfere with the rotation of the same; it has a telescopic movement, and a spring-detent SD is provided to hold it at either limit of its endwise movement in a manner 45 well understood. The bottom of the spindle carries a toothed wheel sh, and when the spindle is in the lower of its extreme positions this wheel engages with the motion-work; in the other extreme position it is free 50 from the motion-work.

In the modification illustrated in Fig. 2 the barrel B has a radial flange RF upon it received between a stationary ring R fixed to the interior of the casing C, and a removable 55 stationary ring SR likewise fixed to the casing. The cover-plate CP of the barrel is fixed to it and has attached to its upturned outer rim CP² the bezel Z.

The movement is kept in place against 60 vertical shift in relation to the casing C by the two rings R and SR and against rotation by a plate PL fixed inside the bottom of the casing and engaging by means of pins p

which enter holes M³ in the bottom plate M² of the movement.

What I claim as my invention and desire to secure by Letters Patent is:—

1. In a time-piece having the winding mechanism located in front of the movement, the combination of the movement frame, a central hollow forwardly projecting pillar fixedly carried on the front plate thereof, a gear wheel for actuating the movement rotatably mounted on the pillar, a main spring surrounding the pillar and having one end attached to the gear wheel, an inclosing member surrounding the main spring and connected to the other end thereof, the inclosing member being rotatable relatively to the movement frame in only one direction, and a bezel mounted on the front of the inclosing member for winding the main spring, substantially as described. 65

2. In a time piece having the winding mechanism located in front of the movement, the combination, with the movement frame, of a central hollow forwardly projecting pillar having a flange at the front end thereof and fixedly carried on the front plate of the movement frame, a gear wheel 70 for actuating the movement rotatably mounted on the pillar, a main-spring surrounding the pillar and attached by one end to the gear wheel, a barrel comprising an inclosing member and a cover-plate therefor, 75 the inclosing member surrounding the main spring and being connected to the other end thereof, and the cover plate being supported at the flange on the pillar and by the inclosing member, the barrel being rotatable about 80 the movement frame in only one direction, and a bezel secured to the front of the barrel 85 for winding the main spring. 90

3. In a time-piece having the winding mechanism located in front of the movement, the combination with the movement frame, of a central hollow forwardly projecting pillar mounted thereon, a gear wheel 95 for actuating the movement rotatably mounted on the pillar, a main spring surrounding the pillar and having one end attached to the gear wheel, a barrel surrounding the main spring and connected to the other end thereof, and rotatable about the movement frame in only one direction, said 100 barrel having a false bottom dividing the same into two chambers, one chamber containing the main spring and the other the teeth of the gear wheel, and a bezel mounted on the barrel for winding the main spring. 105

4. In a time piece having the winding mechanism located in front of the movement, the combination with the casing of a barrel having a radial flange rotatably and removably mounted therein, a movement 110 frame comprising a plate closing the rear 115

end of the barrel, a central hollow forwardly-projecting pillar fixed on said plate and journaled in the front end of the barrel, a gear wheel for actuating the movement 5 rotatably mounted on the pillar, a main spring surrounding the pillar and having one end attached to the gear wheel and the other attached to the barrel, pins fixed on the casing and taking into the movement

frame for preventing the same rotating, the 10 barrel being rotatable relatively to the movement frame in only one direction and having a forwardly projecting rim, and a bezel secured to the rim for winding the main spring, substantially as described. 15

In testimony whereof I affix my signature.

PRIMUS OTTO DORER.
